BURIAL BOX

Jack T. Smith, 711 Mill St., Dallas, Oreg., and Jack C. Doty, 1639 Crittenden St., Albany, Oreg.

Filed Nov. 2, 1959, Ser. No. 58,163

Term of patent 14 years

(Cl. D19—1)

Fig. 1 is a perspective view of a burial box, showing our new design;

Fig. 2 is a side elevational view, to a reduced scale, the opposite side being substantially a mirror image thereof; and

Fig. 3 is an end elevational view, to a reduced scale, the opposite end being substantially a mirror image thereof.

We claim:

The ornamental design for a burial box, as shown and described.
